[57] CLAIM

The ornamental design for an electric guitar, as shown and described.

DESCRIPTION

FIG. 1 is a front elevational view of an electric guitar showing my new design;

FIG. 2 is a left-side elevation view thereof;

FIG. 3 is rear elevational view thereof;

FIG. 4 is a right-side elevational view thereof;

FIG. 5 is an enlarged fragmentary top perspective view;

FIG. 6 is a right-side elevational view of a modified embodiment of the electric guitar illustrated in FIG. 4;

FIG. 7 is an enlarged bottom plan view thereof;

FIG. 8 is an enlarged fragmentary right-side elevation of the bottom portion of the guitar;

FIG. 9 is a top front perspective view thereof; and

FIG. 10 is a bottom rear perspective view.
